EX

DESIGN.

G. S. BARKENTIN.

ORNAMENTATION OF HARDWARE.

No. 16,656.

Patented Apr. 27, 1886.

UNITED STATES PATENT OFFICE.

GEORGE S. BARKENTIN, OF NEW HAVEN, ASSIGNOR TO P. & F. CORBIN, OF NEW BRITAIN, CONNECTICUT.

DESIGN FOR THE ORNAMENTATION OF HARDWARE.

SPECIFICATION forming part of Design No. 16,656, dated April 27, 1886.

Application filed October 6, 1885. Serial No. 179,174. Term of patent 14 years.

To all whom it may concern:

Be it known that I, GEORGE S. BARKENTIN, a citizen of the United States, residing at New Haven, in the county of New Haven and State 5 of Connecticut, have invented and produced a new and original Design for the Ornamentation and Decoration of Articles of Hardware, reference being had to the accompanying engraving, forming a part hereof.

10 The figure is a face view of an article of hardware known as a "cup escutcheon" for a sliding door, showing the ornamentation which I have produced and which I claim.

This invention relates to a design for the 15 ornamentation of various articles of hardware adapted for building purposes and furniture; and the design consists in a beaded sunken panel, as shown in the engraving. The outline of the panel is immaterial, and 20 may be rectangular or irregular in form, and the beading may be plain, as shown in this engraving, or it may include any form of molding. It is, however, so raised above the surface of the sunken panel that it may be polished on a wheel without grinding or abrading 25 the surface of the panel which is inclosed by it. The field or surface of said panel is not plane, but is irregular, and represents a cushion or upholstered work, being depressed at 30 intervals, and at each depression is the representation of a button or knob. Radial lines are shown in these depressions drawn from the button or knob outward and disappearing or merging in the surface of the panel. The 35 most elevated portions of the representation of an upholstered surface are made to represent a textile fabric drawn tightly over the material with which the fabric appears to be stuffed.

40 In the illustration filed herewith I show, also, depending from the lower edge of the article illustrated and across the middle of the panel a representation of a row of tassels, with

which the article illustrated appears to be trimmed. I intend to use such tassels in the 45 various adaptations of this design to articles of hardware, and do not confine myself to the precise arrangement of beading, upholstery, and tassels shown in the engraving.

The illustration is intended to show all the 50 essential features and elements of my design, which may be unitedly applied in various arrangements and combinations to all articles of builders' and cabinet hardware, including knobs, locks, escutcheons, hinges, window- 55 fixtures, door-plates, &c.

In my design there are no lines across the face of the panel separating its surface into checks or sections; but its entire surface, except where concealed by the tassels I have described, is intended and designed to have the appearance of a stuffed cloth, velvet, or leather cushion indented and secured at intervals by knobs or buttons and inclosed within a raised bead or molding; but the whole or a 60 portion of the tassels may be placed without such bead or molding.

I am aware of the Patent No. 10,927, granted to W. M. Smith, November 26, 1878, and of the Patent No. 1,661, granted to Vedder and 70 Ripley, September 23, 1862, and I disclaim what is therein shown and claimed. I have hereinbefore distinguished the features and elements of my invention from the features and elements therein shown and claimed. 75

What I claim is—

The design for the ornamentation of articles of hardware, consisting of the groundwork *a*, representing a stuffed cushion inclosed within a raised border, beading, or molding, and decorated with the tassels *B*, as herein described and shown.

G. S. BARKENTIN.
